UNITED STATES PATENT OFFICE.

ALINE O'SULLIVAN BREAUX, OF NEW IBERIA, LOUISIANA.

BEDPAN.

Application filed October 8, 1926. Serial No. 140,294.

The present invention relates to improvements in bed pans, and has for an object to provide a compact and sanitary arrangement in which both a shield and seat are provided hinged for the purpose of swinging out to gain access to all interior parts of the pan for cleaning.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of the improved pan in the closed position.

Figure 2 is a similar view with the parts open.

Figure 3 is a side elevation of the closed pan.

Figure 4 is a section taken on the line 4—4 in Figure 1.

Figure 5 is a section taken on the line 5—5 in Figure 2, and

Figure 6 is a section taken on the line 6—6 in Figure 1.

Referring more particularly to the drawings, 7 indicates the bottom and 8 the side wall of the improved pan, which is preferably of metal construction and round in form having the slightly flattened sides. The improved shield is indicated at 9, and is shown as hinged at 10 to the front portion of the vertical wall 8. The seat is shown at 11 and is hinged as indicated at 12 to the rear portion of the wall 8, or diametrically opposite the hinge connection 10.

As shown in Figure 3, the side wall 8 is higher at the front or shield side of the pan and lower at the seat side of the pan, and between the shield and seat is arranged the pouring mouth or spout 13. The upper edge of the wall 8 is rolled over outwardly on itself, as indicated at 14 in Figure 6, to provide an enlarged smooth bead. This bead is adapted to receive the trough formed by the rounded portion 15 of the seat, there being a flange 16 on the exterior part of the wall, and a second internal flange 17 extending on the interior part of the wall 8. In other words, this trough construction extends on three sides of the bead 14 and not only prevents the seat 11 from sinking, but also holds it against movement in a horizontal direction. The seat is made concave,

as indicated in Figure 4, and its central forward portion may be supported upon the hollow or other post 18 soldered or otherwise secured to the bottom 7 of the pan. The forward free edge of the seat 11 is also preferably reinforced or stiffened to sustain it from the central supporting post 18 to the side walls 8, and for this purpose an outwardly projecting rounded bead 19 is formed in the seat 11 by striking up the material. This bead is made just inwardly of the forward edge which itself is turned downwardly, and thence upwardly to form the rolled end 20.

The shield 9 at the front is formed in a similar manner having the trough portion 21 along its front curved edge to fit over the upper beaded edge of the wall 8, and also having the upwardly curled rear edge 22 to reinforce and stiffen the rear unsupported edge of said shield. The shield is held removably in place by the clips 23 and 24; while similar clips 25 and 26 are used to hold the side edges of the seat 11 in place.

These clips are hinged or otherwise secured in brackets 27 secured to the side of the pan and they are adapted to swing up and over the trough portions of the seat and shield.

Figures 1 and 3 show the closed position of the seat and shield in readiness for use, while Figures 2 and 5 show the open position of the shield and seat, whereby access may be had to all parts of the pan interior for the purpose of cleaning and sterilizing the same.

It is obvious that various changes and modifications may be made in the details of construction and design of the above specifically described embodiment of this invention without departing from the spirit thereof, such changes and modifications being restricted only by the scope of the following claims.

What is claimed is:

1. A bed pan comprising a pan body, a seat hinged thereto and covering only a portion of the pan, and a shield also hinged to said pan and spaced from the seat.
2. An improved bed pan comprising a pan body having a bottom and a side wall higher at the front than at the rear portion, a shield pivoted to the high front portion of the pan, and a concave seat hinged to the low rear portion of the pan side wall.
3. An improved bed pan comprising a pan

body including a bottom and a side wall having a beaded upper edge, a seat hinged to said side wall and having a trough to receive the bead of the side wall and a stiffened free edge, and means for securing the seat in the closed position.

4. An improved bed pan comprising a pan body composed of a bottom and side wall with beaded upper edge, a concave seat hinged to said side wall and having a trough portion extending on three sides of the bead of the side wall, said seat also having an upwardly pressed bead spaced from its free

unsupported edge and a rolled over edge spaced from said pressed-up bead, and a post in the pan for supporting the intermediate portion of the free edge of the seat.

5. An improved bed pan comprising a bottom and side wall with beaded upper edge, a seat for the pan, a shield spaced from the seat and hinged to the side wall, said shield having a troughed forward edge resting upon and about said bead of the side wall and having a rolled-up rear free edge, and clips for holding said shield in place.
